UNITED STATES PATENT OFFICE

FRANCIS J. PLYM, OF NILES, MICHIGAN, ASSIGNOR TO THE KAWNEER COMPANY, OF NILES, MICHIGAN, A CORPORATION OF MICHIGAN

WINDOW CONSTRUCTION

Application filed April 3, 1929. Serial No. 352,190.

This invention relates to window constructions and more in particular to a novel construction of window in which the window sashes are placed in position after the masonry and plaster work have been finished, and in which the sash or sashes are adapted to be swung inwardly, allowing for the easy repair and washing of the windows.

In the present day construction of windows, either the balanced type, or casement type, or those in which the sash swings outwardly, considerable difficulty is experienced in repairing the windows and in washing the same. Especially is this true in high building constructions. In the washing of the balanced windows, it is necessary for the window washer to climb through the opening and position himself on the outer ledge or sill. This is extremely hazardous, and frequently a fatality has occurred. In the higher building constructions, it is extremely difficult for the window washers or the person repairing the window to keep a proper footing in view of the high wind velocity. This is true even though the person be equipped with the well known straps or safety devices now in use.

In the construction, wherein the sash swings outwardly, it is extremely difficult to wash the windows on the outer side. Also there is always the danger of the glass being broken and falling upon pedestrians, if the window is slammed by wind, etc. It is extremely hazardous to repair such a construction and thus they have not come into common use in buildings of any height.

Among the objects of my invention are to provide a novel construction of window frame and sash, the steel frame buck being incorporated into the permanent construction of the building, the same being placed in the opening to guide the plasterers and masons in doing their work. After these workmen have completed their task, other workmen will come later with the finished windows which are to be attached to the buck. Thus the windows will be placed in the building at the time the woodwork and finished work is being done, rather than at the time the brick or stone work is erected.

Thus I believe the hazard and damage that is generally incident to the erection and placing of the windows prior to the completion of the stone, brick and plaster work.

A further object of my invention is to provide a novel construction of sash and meeting rail, the meeting rail forming a permanent part of the window frame construction, and the sash being hinged to allow for the swinging inwardly of the window.

Among the further objects of my invention are to provide a novel construction of hinge mechanism adapted to receive the hinge portion on the sash; further to provide a novel construction of window, provided with a swingable window ventilator at either the bottom, top, or both, and which window ventilators may be swung inwardly to allow for the proper ventilation. The lower ventilating sash is provided with a counter-balance so as to automatically close the sash, although such construction may also be provided on the upper ventilator, if desired.

A further object of my invention is to provide a window construction which is fire-proof and weather-proof; further to provide a novel means and method of holding the window panes in position; further to provide a construction of maximum simplicity, efficiency, and ease of assembly and operation; and such further objects, advantages and capabilities as will later more fully appear and are inherently possessed thereby.

My invention further resides in the combination, construction, and arrangement of parts illustrated in the accompanying drawings, and while I have shown therein a preferred embodiment, I desire it to be understood that the same is susceptible of modification and change, without departing from the spirit of my invention.

In the drawings:

Fig. 1 is a view in front elevation of my novel window construction;

Fig. 2 is a view in side elevation of my window construction, the sash and window ventilator being shown as swung inwardly;

Fig. 3 is a fragmentary view in vertical cross section taken on the line 3-3 of Fig. 1;

Fig. 4 is a fragmentary view in horizontal cross section taken on the line 4—4 of Fig. 1;

Fig. 5 is a view in front elevation of my novel construction of window provided with 5 an upper and lower ventilator;

Fig. 6 is a view in side elevation of the construction disclosed in Fig. 5, the window ventilators and sash being shown in open position;

10 Fig. 7 is a view in vertical cross section taken on the line 7—7 of Fig. 5.

Referring more in particular to the construction disclosed in Figs. 1 to 4 inclusive of the drawings, the numeral 1 refers to steel 15 bucks, which are set in the side walls of the building construction, and form a permanent part thereof. Connected to the bucks is a frame comprising a top member 2, side members 3 and a sill 4. Any suitable means of 20 connection, such as bolts 5, may be used. The top portion of the frame is provided with a longitudinal flange 6, a hinge member 7, a stop or shoulder 8 and a face flange 9. The side plates 3 are provided at the sides there- 25 of with an inner flange 10 and an outer flange 11, and intermediate the same with a longitudinal groove or channel 12 and a stop or shoulder 13, the plates being attached to the side bucks by any suitable means 14 and 30 15, such as bolts or the like. Mastic cement 16 provides a filler between the flanges 9 and 11, and the bucks and masonry or brick work 17. The frame construction including the top 2 and sides 3 forms the head and side 35 jambs of the window.

The sill 4 comprises a plate or member having downwardly extending flanges 18 and 19, the flange 18 contacting with a side of the buck. Adjacent the flange 18, I provide a 40 gutter 20, and a hinge member 21. Intermediate the two flanges 18 and 19, I provide a shoulder portion 22 adapted to form a stop and seat for a portion of the window ventilator.

45 Located near the bottom of the window frame, I provide a mullion 23 having outwardly and rearwardly bent portions 24 and 25, and a face plate 26 provided with a bead 27. A plate 28 is positioned intermediate 50 the bent portions 24 and 25 and sides of the bead 27, to give the same rigidity. This mullion forms a part of the window frame construction and is connected to the side jambs. As disclosed clearly in Fig. 3, the 55 backwardly bent portions 24 and 25 of the mullion form longitudinal recesses 29 and 30 respectively to intercept the sashes, as later more fully explained.

Located in the upper part of the window 60 frame, I provide a sash 31 adapted to be swingably held by means of a hinge member 32 fitting into and cooperating with the hinge member 7 on the frame. This construction allows the sash to be hung in the frame 65 or to be disconnected therefrom, and to be

swung inwardly when assembled. The inner two sides 33 and the bottom 34 of the inner unit of the sash 31 are provided with a longitudinally extending lip or projection 35 and 36 respectively, adapted to seat in the 70 longitudinal groove 12 of the side jambs, and in the longitudinal groove 29 of the mullion. The outer unit comprises a channel-shaped upper member 37 provided with the hinge member 32 and a seat 38, and a rib or flange 75 39, this seat and flange providing a means for holding the glass in position. The sides and bottom of this outer member provide a seat 40 and flange 41, while the front face or unit 42 of the sash is adapted to contact at 80 the top against the stop or shoulder 8, on the sides against the stop or shoulder 13, and at the bottom against the face plate 26 of the mullion. This provides a weather-tight construction. A pane of glass 43 is held in the sash by means of the inner and outer units, which are connected together by any suitable attaching means 44 such as bolts screws or the like. Felt or other weather strip 45 is provided for firmly but yieldably holding the glass in 85 position, and allowing for vibration, expansion and contraction thereof.

Mounted in the bottom of the frame, I provide a window ventilator 46 having its inner unit constructed similar to the inner 90 unit of the sash, but hinged at the bottom by means of a hinge member 47 adapted for engagement in the hinge 21 on the window sill. A flange 36^a on the upper face 34^a of the sash is adapted to be inserted in the longitudinal 95 groove 30 of the mullion, while the outer unit 42^a at its upper end is adapted to abut the inner surface of the face plate 29 of the mullion, and the lower end of this unit is adapted to abut against the shoulder or stop 22 on the 100 sill, thus forming a weather-tight connection. As disclosed in Fig. 3, the upper sash and the ventilator sash are similar in construction, with the exception that the hinge member 47 on the ventilator sash is not constructed integral with the channel-shaped member 48, but forms a part of the inner unit of the sash and is connected to the channel member by any suitable means 49 such as bolts, screws, etc. Thus the stop or flange 39^a is not 105 doubled-back as is the stop or flange 39 of the upper sash but forms a single thickness of metal. The seats 38^a and 40 in conjunction with the inner unit and the stops or flanges 39^a at the bottom, and 41 at the top and sides, 110 hold the glass 50 in position.

In Figs. 5, 6 and 7, I disclose a construction, wherein I provide a ventilator at both the top and bottom of the window frame. In this construction, it is necessary to provide a 115 mullion 51 provided with an upper hinge member 52 and a lower hinge member 53, and a face plate 54. The ventilator sash 55 is provided with a hinge member 56 adapted to engage with the hinge member 52 on the mullion, 120

and thus allow the ventilator sash to be swung inwardly. This ventilator and window sash are similar in construction to the lower ventilator and window sash, and like reference characters have been applied.

In order to make the ventilator or ventilators normally self-closing, I provide a triangular metal piece 57 provided with a flange 58 attached to the outer face 42 of the ventilator sash by any suitable means 59. Connected to this triangular piece, I provide a weighted member 60, which may be hollow and filled with some heavy material, such as lead or iron, so that this ventilator sash will be counter-balanced, and when open, this counter-balance will automatically cause the window to close itself unless some means are provided for holding it open. When the window swings inwardly, the weighted member 60, which as shown is offset with relation to the metal piece, will contact with the flange 11 on side jambs of the window frame, this weighted member thus having the double function of normally closing the window and acting as a stop when the window is open. An auxiliary spring or tension member 61 may be provided within the sash at one or both sides, and is connected to the sill 4 to normally close the sash. As shown in Fig. 4, this tension member will bear against the face 42 to force the sash into closed position.

In order to hold the window open, I provide some means, such as a bar or arm adapted to hold the window in various positions of adjustment. If desired, this bar may be provided with a fusible link, so that in case of fire, this link will be melted away and allow the counter-balance or tension member to automatically close the sash. As shown, the metal piece is pivoted adjacent the base of the ventilator sash so as to allow for the opening and closing thereof. Although I have only shown this construction in combination with the lower ventilator, it is to be understood that the same is adapted for use with either or both of the ventilators, as desired.

From the above description, and the disclosure in the drawings, it will be readily seen that I have provided a unique construction of window frame and sashes. The sashes are hung at the time the finishing work is being performed on the structure, so there is little likelihood of damage to the windows. The hinge portion on the sashes may be quickly and easily inserted in the hinge portion on the window frame, and when so inserted, there is no possibility of the sash becoming disengaged except by raising the same to a substantially horizontal plane and lifting it out of engagement with the hinge on the frame. The frame and sashes are shown as constructed of metal, allowing for greater rigidity, and being hollow, are thus relatively light in weight. There is no possibility of the weather securing access to the interior of the

building whenever the sashes are closed. Wherever desired, a weathering strip 62 may be provided. In order to allow for the drainage of the mullions 26 and 51, I provide drain openings 63 in the plate 28.

By providing a construction in which the sash or sashes swing inwardly, the same may be repaired and washed easily, and readily. There is no danger to pedestrians as the glass cannot break and fall exterior of the building. The bucks which are generally of steel, are placed in the opening to guide the plasterers and masons in doing their work. The frame is then connected to the bucks, and thereafter, the sashes are hung in position. The channel for the reception of the sashes is generally filled with some material such as asbestos plaster or the like, thus affording a weather-tight and fireproof sealing means.

Having thus disclosed the invention, I claim:

1. In a window construction, a frame formed to provide an upper, lower, and intermediate opening of greater size than said first mentioned openings, a window sash insertable in said intermediate opening, ventilators in said upper and lower openings, and hinge means permitting the swinging inwardly of said sash and ventilators.

2. In a window construction, a frame provided with a pair of mullions forming an upper, lower and intermediate opening, hinge members on said mullions, a window sash insertable in said intermediate opening, ventilators mounted in said upper and lower openings and hinge members on said sash and ventilators engaging the hinge members on said mullions permitting the opening thereof.

3. In a window construction, a frame therefor including a sill, a ventilator sash hingedly connected to said sill for allowing the swinging thereof, and a counter-balance for normally closing said sash.

4. In a window construction, a frame therefor including a sill, a ventilator sash hingedly connected to said sill for allowing the swinging thereof and a counter-balance for normally closing said sash, said counter-balance comprising a triangular plate and a weighted member attached thereto.

5. In a window construction, a frame therefor including a sill, a ventilator sash hingedly connected to said sill for allowing the swinging thereof, and means for automatically closing said sash.

6. In a window construction, a frame therefor, having parts provided with elongated grooves, a metal sash comprising a pane seating section provided with a flange for engaging a pane of glass, a pane holding member having angle portions adapted to hold said pane in position, a leg of said angle adapted to be received in said grooves and hinge means on said frame and sash for permitting the swinging inwardly of the sash.

7. In a window construction, a frame adapted to be inserted in a window opening and provided with a mullion, window sashes in said frame, said sashes provided with a pane seating section, and a glass holding member secured to said sections and having a part overlapping a portion of said mullion to provide a weather-tight joint. 70
8. In a window construction, a frame provided with side jambs and a mullion, sashes in said frame, said sashes provided with a pane seating section, and a glass holding member connected to said sections and having a flange overlapping portions of said mullion and side jambs for providing a weather-tight joint therebetween. 75
9. In a window construction, a frame provided with side jambs and a mullion, sashes in said frame, said sashes provided with a pane seating section, said mullion and side jambs having an elongated groove, and a pane holding member connected to said sections; said member provided with a flange cooperable with said groove for effecting a tight joint therebetween. 80
10. In a window construction, a frame in a window opening, a sash in said frame, said sash provided with a pane seating section, and a pane holding member secured to said section, said member having a hinge part cooperating with a hinge on said frame to allow swinging of said sash. 85
11. In a window construction, a sash comprising a pane seating section, and a pane holding member, said member having a part bent to form a hinge to permit swinging of said sash. 90
12. In a window construction, a frame in a window opening and provided with elongated grooves, a sash in said frame, said sash having a pane seating section, and a pane holding member secured to said section, said member having a part bent to form a hinge element for swinging said sash, said member having flanged parts cooperating with said grooves to provide a tight joint between said sash and frame. 95
13. In a window construction, a sash comprising a pane seating section, said section having a part bent to form a hinge element for swinging said sash, and a pane holding member secured to said section. 100
14. In a window construction, a sash comprising a pane seating section, said section having a part bent upon itself to provide a pane stop and a part bent to provide a hinge element for swinging said sash, and a pane holding means secured to said section. 105
15. In a window construction, a frame adapted to be inserted in a window opening, said frame having parts bent to provide a hinge element, and a closure member in said frame provided with a hinge element adapted to cooperate with the hinge element of said frame whereby said member may be swung away from said frame. 110
16. In a window construction, a frame adapted to be inserted in a window opening, said frame provided with a top member having parts bent to provide a hinge element, and a sash member in said frame and provided with a hinge element adapted to cooperate with said hinge element of said top member for movement of said sash in said frame. 115
17. In a window construction, a frame adapted to be inserted in a window opening, said frame provided with a top member having a part bent upon itself to provide a hinge element, and a sash member in said frame and provided with a hinge element engaging with the hinge element of said top member whereby said sash may be moved in said frame. 120
18. In a window construction, a frame adapted to be inserted in a window opening, said frame provided with a top member and a sill, said top member and sill having parts bent to provide hinge elements, and closure members provided with hinge elements engaging with the hinge elements of said top member and sill whereby said closure members may be moved in said frame. 125
19. In a window construction, a frame adapted to be inserted in a window opening, said frame provided with a top member and a sill, said top member and sill having a part bent upon itself to provide a hinge element, and closure members provided with hinge elements engaging the hinge element of said top member and sill whereby said closure members may be moved in said frame. 130
20. In a window construction, a frame adapted to be inserted in a window opening and provided with a mullion, said mullion comprising a face plate, an inner member, and a plate therebetween, and closure members carried in said frame. 135
21. In a window construction, a frame adapted to be inserted in a window opening and provided with a mullion, said mullion comprising a beaded face plate, a beaded inner member, and a plate engaging with the beads of said members, and closure members carried in said frame. 140
22. In a window construction, a frame adapted to be inserted in a window opening and provided with a mullion, said mullion comprising a beaded face plate, a plate engaging in said bead, and an inner member adapted to fit over said plate, said member provided with grooves, and closure members in said frame having parts engaging in said grooves. 145
23. In a window construction, a frame adapted to be inserted in a window opening and provided with a mullion, said mullion comprising a beaded face plate, a plate engaging in said bead, and an inner member fitting over said plate and having the edges thereof bent to provide grooves, and closure members carried in said frame. 150

members in said frame and having parts engaging with said grooves.

24. In a window construction, a frame adapted to be inserted in a window opening and provided with a mullion, said mullion comprising a beaded face plate having laterally extending flanges, a plate engaging in said bead, and an inner member provided with grooves fitting over said plate, and closure members in said frame, said closure members having parts engaging in said grooves and contacting with said flanges for providing a weather-tight joint.

25. In a window construction, a frame adapted to be inserted in a window opening and provided with a mullion, said mullion comprising a beaded face plate having laterally extending flanges, a plate engaging in said bead, and an inner member provided with grooves fitting over said plate, and sashes in said frame, said sashes comprising inner and outer members adapted to engage in said grooves and contact with said flanges respectively.

26. In a window construction, a frame for a window opening and provided with a grooved mullion and side jambs, and a sash in said frame, said sash comprising a pane seating section and a pane holding member, said member having a part bent to provide a hinge for swinging said sash and other parts bent to engage in said grooves.

27. In a window construction, a frame for a window opening and provided with a sill, a sash member hingedly connected to said sill, counter-balance means for closing said sash, and resilient means adapted to assist in closing said sash.

28. In a window construction, a frame for a window opening and provided with a sill, a sash member hingedly connected to said sill, and a counterweight means secured to said member for closing the same, said means adapted to contact with said frame to provide a stop for said sash.

29. In a window construction, a frame for a window opening and provided with a sill, a sash member hingedly connected to said sill, a plate secured to and extending laterally of said member, said plate having an enlarged outer edge portion for counter-balancing said sash and adapted to contact with said frame to provide a stop for said sash.

30. In a window construction, a frame for a window opening and provided with a sill, a sash member hingedly connected to said sill, a plate secured to and extending laterally of said member, said member having its outer edge bent to provide an enlarged tubular part adapted to enclose weighty material for counter-balancing said sash for closing the same.

31. In a window construction, a frame for a window opening and provided with a sill, a sash member hingedly connected to said sill, and resilient means secured to said sill

and adapted to bear against said sash for closing the same.

32. In a window construction, a frame adapted to be inserted in a window opening, said frame having parts bent to provide a hinge element, and a sash in said frame, said sash having a part bent to provide a hinge element adapted to cooperate with said hinge element of said frame whereby said sash may be moved therein.

33. In a window construction, a frame adapted to be inserted in a window opening, said frame having parts bent to provide a hinge element, a sash member comprising an inner and outer member adapted to hold a pane of glass therebetween in said frame, one of said members having the outer portion thereof bent to provide a hinge element adapted to cooperate with the hinge element of said frame whereby said sash may be moved therein.

34. In a window construction, a sash comprising a pane seating section, and a pane holding member, said member having hinge means to allow swinging of said sash.

35. In a window construction, a sash comprising a pane seating section, and a pane holding member, said member having a hinge element to allow swinging of said sash.

36. In a window construction, a frame adapted to be inserted in a window opening and provided with a mullion, said mullion comprising a face plate, an inner member, and a plate spanning between said face plate and member, and closure members carried in said frame.

37. In a window construction, a frame formed to provide a plurality of openings, a window sash insertable in one of the openings, ventilators positioned in the other openings, and hinge means to allow swinging of said sash and ventilators.

38. In a window construction, a frame having a portion formed to provide a hinge element, and a sash member in said frame and having a part formed to provide a hinge element adapted to cooperate with the hinge element of said frame to allow swinging of said sash.

39. In a window construction, a frame having a top rail and sill, said rail and sill having portions formed to provide a hinge element, an upper and a lower sash member in said frame, said members having parts formed to provide hinge elements adapted to cooperate with the hinge elements of said rail and sill to allow swinging of said members in said frame.

In witness whereof, I hereunto subscribe my name to this specification.

FRANCIS J. PLYM.
